CLAIM

The ornamental design for an embossed panty liner, substantially as shown and described.

DESCRIPTION

FIG. 1 is a perspective view of an embossed panty liner
showing my new design;

FIG. 2 is a traverse end view of the embossed panty
liner; the opposite end being identical;

FIG. 3 is a longitudinal side view of the embossed panty
liner; the opposite side being identical;

FIG. 4 is a top plan view of the embossed panty liner;
and

FIG. 5 is a bottom plan view of the surface opposite that depicted in FIG. 4 of the embossed panty liner.
